WASHING MACHINE

Elbert L. Hyde, Shaker Heights, Ohio, assignor to
The American Laundry Machinery Company,
Norwood, Ohio, a corporation of Ohio

Application November 18, 1937, Serial No. 175,349
Renewed March 15, 1939

3 Claims. (CL. 68—27)

This invention relates to improvements in washing machines and more particularly to a machine having a plurality of compartments in which the depth of the detergent bath varies automatically during a washing operation due to the arrangement of the parts.

An object of the present invention is to provide a plurality of washing cylinders rotatable in a single casing and wherein the bottom of the casing forms compartments for holding the detergent bath and wherein the washing cylinders reverse their direction of rotation and are so related to partition means between the compartments that detergent is carried from one compartment to another so as to vary the depth of the detergent bath in any one compartment during the washing process.

Other novel features of my device will be apparent from the accompanying drawings and specification and the essential features will be set forth in the claims.

In the drawings, Fig. 1 is a front elevation of a washing machine embodying my invention; Fig. 2 is a vertical sectional view taken through the machine of Fig. 1; Fig. 3 is a top plan view of the machine of Figs. 1 and 2 with parts broken away to show the structure; while Fig. 4 is a diagram of the reversing circuits for the driving motor.

There are certain advantages derivable from the housing of two or more rotatable washing cylinders in a single casing together with the provision of a reversing drive for the cylinders. I have taken advantage of this arrangement to provide partition means in the bottom of the casing forming a separate detergent bath beneath each washing cylinder, the partition being so arranged that upon rotation of two adjacent cylinders in the same direction detergent is carried over the partition so as to lower the level in one compartment while at the same time raising the level in an adjacent compartment. Thus in the usual washing operation where the direction of cylinder rotation is periodically reversed, the detergent bath in which the articles are washed is alternately raised and lowered in depth, thus performing certain desirable functions in a washing operation.

While it will be understood that my device may be applied to more than two cylinders, I have illustrated a single casing 10 housing foraminous cylinders 11 and 12. These cylinders are mounted for rotation in the casing by means of gudgeons 13 and 14 secured to the rear heads of cylinders 11 and 12 respectively. Rigidly connected to the gudgeons 13 and 14 are the drive gears

15 and 16, each of which meshes with a pinion 17 suitably mounted for rotation on the casing frame on shaft 18. Also mounted on shaft 18 is a large pulley 19 which is connected by belt drive 20 with a small pulley 21 on the shaft 22 of motor 23 which in the present instance is shown mounted on the top of the casing.

For loading and unloading the washing cylinders the front cylinder head is provided with openings opposite the doors 24 and 25. These doors of course are swung on hinges and suitably sealed during a washing operation. The forward end of each cylinder is preferably provided with a collar 26 which engages rollers mounted at points 27 so as to support the forward end of the cylinder when loaded.

Any suitable means may be provided for reversing the direction of drive of the washing cylinders and for this purpose I have illustrated the structure more thoroughly shown, described and claimed in Patent No. 2,007,591 granted July 9, 1935, to W. P. Beattie. This control mechanism may be mounted in a housing 28 mounted on the casing and Fig. 4 shows a diagram of the control circuits. Motor 23 is an A. C. motor, three-phase, which is reversed by reversing two of its leads. The circuits to said motor come from the source 29 by way of a manually operated main switch 30 and two sets of normally open contactors marked respectively 31 and 32. These contactors are actuated respectively by relays 33 and 34 in the two branches 35 and 36 of a control circuit including a switch 37 connected to the casing doors in such a manner as to be open when the doors are open and closed when the doors are closed, and also by way of an overload throw-out switch 38 which is normally closed but which is adapted to open upon abnormal current flow to the motor for any cause. A pilot motor 39 is in a circuit across two of the leads as shown. In operation of the system one or the other of the relays 33, 34 is energized to close its set of contactors 31, 32 as the case may be by closing one or the other of the branch circuits 35, 36 which is effected by manipulation of the pairs of switch members 40, 41 in one pair and 42, 43 in the other pair. These pairs of switches are operated so as to alternately close one and open the other by means of suitable cams actuated by pilot motor 39 which is constantly running during a washing operation. These cams and their operation are more fully described in the patent referred to. The result of this control system is that when the cylinders are loaded and the doors closed and

the current turned on, motor 39 runs constantly and reverses the rotation of motor 23 so that cylinders 11 and 12 rotate first both in clockwise direction and then both in counterclockwise direction, this reversal continuing periodically throughout the washing operation.

It will be noted that the bottom of casing 10 is provided with partition means 44 which forms separate compartments or pockets for the detergent bath beneath each washing cylinder. Preferably the partition walls follow closely the curvature of the cylinder and are slightly spaced therefrom. Preferably also the walls of the casing at points 45 also closely follow the curvature 15 of the washing cylinders to produce a better washing action. Normally the casing 10 is supplied with a detergent bath which in a quiescent state is at a level below the top of partition 44. With the two cylinders rotating in the same direction 20 the tendency is for one of the cylinders to carry liquid up one face of partition 44, throwing it over the top where it is carried down the other side by gravity and by the rotation of the other cylinder. It results from this action that with the 25 parts as viewed in Fig. 2, with both cylinders rotating counterclockwise detergent will be carried from the compartment below cylinder 11 over into the compartment beneath cylinder 12 so as to make the detergent bath deeper in the right-hand compartment and shallower in the left-hand compartment. Upon reversal of the motor 30 drive these conditions will be reversed.

Preferably the washing cylinders are supplied with lifting ribs 46 for the well known purpose of 35 lifting articles being washed and dropping them into the detergent bath. With my improved mechanism herein disclosed the articles being washed are alternately dropped into shallow and deep detergent baths. I find that this results in 40 an effective washing operation as when the bath is shallow in one of the compartments the clothes are dropped with the resultant beating action, whereas when the detergent bath is deeper, the dirt released by the beating action is washed out 45

by the deeper bath. This action goes on alternately throughout the washing process.

The usual accessories are supplied for introducing liquid, soap, bleaches and the like into the casing 10 and for draining the same. For instance, I have shown pipe connections at 47 for the introduction of hot and cold water to the casing, trough 48 opening into the casing for introduction of soap and the like and also dump valves at 49 which may be actuated by any suitable means, as for instance by the pedal 50.

What I claim is:

1. In a washing machine, a casing, a pair of foraminous cylinders rotatably mounted in said casing on parallel axes, means for rotating said cylinders in the same direction, means for reversing the direction of cylinder rotation, and a partition between said cylinders forming two separate compartments in the bottom of said casing, said partition being so constructed and arranged 15 that liquid is carried over said partition by cylinder rotation.

2. In a washing machine, a casing, a pair of foraminous cylinders rotatably mounted in said casing on parallel axes, means for rotating said 25 cylinders in the same direction, means for periodically reversing the direction of cylinder rotation, a partition between said cylinders having surfaces parallel to said axes and conforming to the curvature of said cylinders and slightly spaced 30 therefrom, said partition separating two non-communicating compartments in the bottom of said casing, and said partition being of such a height that liquid is carried over said partition from one compartment to the other by cylinder 35 rotation, when the quiescent liquid level in said one compartment is lower than the top of said partition.

3. The combination of claim 1 wherein said cylinders have means on their inner walls for 40 lifting and dropping articles washed therein, whereby said articles are at alternate reversals of rotation dropped into a detergent bath of different depth.

ELBERT L. HYDE. 45
